(57) **CLAIM**

The ornamental design for a container with cap, as shown and described.

DESCRIPTION

FIG. 1 is a perspective view of a container with cap according to my new design, shown in a closed configuration;

FIG. 2 is a front and back view thereof;

FIG. 3 is a left side and right side view thereof;

FIG. 4 is a top view thereof; and

FIG. 5 is a perspective view of the container, shown independent of the cap to show features not shown when combined;

FIG. 6 is a front view thereof;

FIG. 7 is a rear view thereof;

FIG. 8 is a right side view thereof;

FIG. 9 is a left side view thereof;

FIG. 10 is a top view thereof; and

FIG. 11 a perspective view of a cap, shown independent from the container;

FIG. 12 is a front and back view thereof;

FIG. 13 is a left side and right side view thereof;

FIG. 14 is a top view thereof;

FIG. 15 is a bottom view thereof; and

FIG. 16 is a perspective view of the container according to my new design;

FIG. 17 is a front and back view thereof;

FIG. 18 is a left side and right side view thereof; and,

FIG. 19 is a top view thereof.

(Continued)

The broken lines illustrate parts of the article that form no part of the claimed design. The dot-dash lines represent the boundaries of the claim and form no part thereof.
